UNITED STATES PATENT OFFICE

152,247

DESIGN FOR A TRIPOD HEAD FOR A CAMERA OR SIMILAR ARTICLE

Stanley J. Flesh, Chicago, Ill.

Application April 30, 1948, Serial No. 146,075

Term of patent 7 years

(Cl. D61—1)

To all whom it may concern:

Be it known that I, Stanley J. Flesh, a citizen of the United States, residing in Chicago, county of Cook, and State of Illinois, have invented a new, original, and ornamental Design for a Tripod Head for a Camera or Similar Article, of which the following is a specification, reference being had to the accompanying drawing, forming part thereof:

Fig. 1 is a side perspective view of a tripod head for a camera or similar article, showing my new design;

Fig. 2 is an end view;

Fig. 3 is a side view opposite to that shown in Fig. 1; and

Fig. 4 is a top plan view thereof, the handle being shown broken away for convenience of illustration.

I claim:

The ornamental design for a tripod head for a camera or similar article, substantially as shown.

STANLEY J. FLESH.
